UNITED STATES PATENT OFFICE.

PATRICK J. KELLEY, OF MANSFIELD, OHIO, ASSIGNOR TO THE OHIO BRASS COMPANY, OF MANSFIELD, OHIO, A CORPORATION OF NEW JERSEY.

GALVANIZING MECHANISM.

Application filed March 12, 1925. Serial No. 14,989.

My invention relates to process and apparatus for coating castings with a thin and uniform layer of metal such as zinc, tin, etc.

The objects of my invention are to provide an apparatus by means of which a quantity of castings may be coated at a time and with a uniform coating of metal, and in which all excess metal is removed from the castings, giving them a smooth and attractive appearance, and to secure these results with economy and small effort upon the part of the operator.

My invention resides in the new and novel construction, combination and relation of the parts more fully hereinafter described and disclosed in the accompanying drawings.

In the drawings:

Fig. 1 is a side view in partial section of my invention shown as mounted upon a pedestal.

Fig. 2 is a top plan view of my invention as shown in Fig. 1.

Fig. 3 is a side plan view of my invention, but showing the opposite side from that shown in Fig. 1.

Fig. 4 is an end view of my invention looking toward the right hand end of Fig. 2.

Fig. 5 is a detailed view of a part of the operating mechanism and Fig. 6 is a section of the same on the line 6—6 of Fig. 5.

Figs. 7, 8, 9 and 10 are various enlarged views of the casting container.

Fig. 11 is a partial vertical section along line 11—11 of Fig. 3 showing the pivotal mounting of the horizontal bed upon the pedestal 2.

I provide a furnace represented by the numeral 1, which may be of the usual type, consisting of a steel or iron tank mounted within the furnace walls and having an open top and which is heated by solid, gaseous or liquid fuel. My furnace is not necessarily of any special construction so long as it is possible for access to the molten zinc within by the casting container later described. I mount my invention upon a pedestal of any suitable sort adjacent to the tank 1 so that the casting container will be mounted over the molten bath. In Fig. 1 I have shown my invention as mounted upon the brick pedestal 2. Upon the pedestal 2 is a base casting 3 secured thereto by the bolts 4. The base casting is formed with a central hollow

boss 5 in which is mounted a pivotal member 6 which is free to be rotated about a vertical axis. The upper portion of the pivotal member 6 is formed with a boss adapted to fit between the lugs 7, shown in Fig. 5, and the pivotal member is provided with a transverse hole in the lugs 7 also to receive the pin 8 by means of which the lugs 7 are secured to the pivotal member 6 such that the lugs may pivot in a vertical plane about the horizontal axis of the pin 8. The lugs 7 form downwardly projecting members of the plate 9 which is secured to the longitudinally disposed and spaced channel beam 10 by means of the bolts 11. The plate 9 tends to hold the longitudinally disposed channels 10 in a fixed and spaced relation and the channels form the bed upon which I construct the balance of my invention. The channels 10 are further secured in spaced relation by means of the cross-bar 12 secured to the channels by means of the bolts 13 and other cross-bars may be employed also, but which I do not show as it is merely confusing.

It will be appreciated that thus far I have formed a bed upon which to build my invention and which bed is pivotal in both a horizontal and vertical direction. The pin 8 is made stationary with the pivotal member 6 and upon the end of the member 8 is rigidly mounted a catch plate 14 provided with a plurality of notches 15.

To the under side of the channels 10 are two transversely disposed angle members 16 and through these angle members project a rod 17 which is movable longitudinally and held in an advanced position by the spring 19. The right hand end of the rod 17 is turned downward to form a handle 20 and the opposite end is secured to a movable link 21 pivoted to the frame 10 to act as a support and is also provided with a tooth 22 adapted to engage the notches 15 in the catch plate. It will be observed from Fig. 1 that I have shown the catch plate provided with two notches 15 and the lower one when engaged by the tooth 22 will hold the machine bed in a substantially horizontal position and when the upper notch is engaged by the tooth 22 the machine will be held in an oblique position, as indicated by the line A—A, which represents the longitudinal axis of the machine when it has been posi-

tioned with the tooth 22 in the upper notch and the casting container submerged in the metal tank.

Mounted upon the left hand end of the channel members 10 are two bearings 23 and 24 and these are secured in position upon the channels 10 by means of the bolts 25. Mounted in the bearings 23 and 24 is a hollow shaft 26. Upon the right hand end of the shaft 26 is rigidly mounted a bevel gear 27 and mounted upon the left hand end is the casting container 28. The container 28 is so mounted upon the shaft 26 that the shaft extends through the container and the container is secured to the shaft by means of the flange 29 which may be secured to the container by means of the bolts 30, and secured to the shaft in any suitable manner as by means of a key 30' and set screw or a set screw alone.

Mounted upon the transverse shaft 31 secured to the channels 10 is a beveled pinion 32 which meshes with the bevel gear 27. On each end of the shaft 31 is mounted a pulley 33 and 34 respectively and the members 31, 32, 33 and 34 rotate simultaneously and in the same direction. The pulleys 33 and 34 are adapted to receive a belt 35 and 36 respectively. Upon the frame composed of the channels 10 and at the opposite end from the casting container 28 is mounted an electric motor 37 or other source of power for operating the apparatus. The belt 36 I show as connected directly to the pulley 38 on the motor, but the belt 35 is connected to the motor through the medium of gearing so as to give the shaft 31 a materially reduced speed when driven by the belt 35 as compared with its speed when driven by the belt 36. The gears are shown as 39, 40 and 41, the latter being connected to the pulley 42 to which the belt 35 is directly connected. Transversely disposed with respect to the frame is a cross shaft 43 and secured thereto is an operating lever 44. To the lever 44 is pivoted a pulley 45 to engage the belt 36 when the lever is moved upwardly and, therefore, acts as a belt tightener for the belt 36. Secured to the shaft 43 at the other side of the frame is a lever 46 to which is secured a pulley 47 which engages with the belt 35 and when in engagement therewith acts as a belt tightener for the belt 35. From this, it will be recognized that the belts 35 and 36 normally are loose belts and when the lever 44 is in a middle position the pulleys 45 and 47 will be out of engagement with the belts and the motor is free to rotate without rotation of the cross shaft 31, therefore, if the operator wishes to rotate the casting container 28 at a slow speed he moves the operating handle 44 downward, and if he wishes to operate at a high speed he will move the handle 44 upwardly.

The slow operation of the casting container 28 is required largely while the castings are submerged in the tank of molten metal, and as I prefer to have this submergence for a considerable length of time, I provide a rack 48, shown in Fig. 5, with a plurality of teeth 49 such that the handle 44 when in a downward position, in which position the casting container 28 rotates slowly, will engage with the teeth 49 and be held in a downward position, thus relieving the operator.

It is desirable to hold the casting container 28 in a certain position while loading castings therein and in another position when dumping the castings, therefore, in order to not only hold the container in a predetermined position, but to stop it quickly and as near such position as possible, I provide a brake which will engage the pulley 33 when the handle 44 is in mid position and in which position both belts are loose. The brake referred to comprises a brake arm 50 pivoted at 51 and having a shoe 52 to engage the pulley 33. Mounted longitudinally upon the frame in suitable bearings is a shaft 53 provided with an upright member 54 and 55 at its respective ends and rigidly secured to the shaft 53. To the upper end of the member 54 is a transverse member 56 which connects with the brake arm 50 and is pivotally connected to the brake arm and to the member 54. The member 55 is positioned adjacent the bracket 48 and is shown in Fig. 5 by the dotted lines. When the operating handle 44 reaches mid position it is possible to move it sideways and to the right, as shown in Fig. 5, into the slot 57 and as it is moved to the right it will engage the upper end of the member 55 and move it to the right. When this takes place the shaft 53 is rotated and the upper end of the member 54 is moved to the right and with it the transverse rod 56 thereby moving the brake beam 50 about its pivotal point 51 and the brake shoe 52 will be moved into engagement with the pulley 33.

Secured to the end of the channel iron frame is a cross bar 58 and projecting from this is a handle 59 used in pivoting the device about its horizontal and vertical pivotal axes. To the member 58 is secured the rack 48, as shown in Fig. 5.

Mounted upon the cross member 58 and in pivotal relation thereto is a depending handle 60. Rigidly mounted upon the member 58 is a member 61 provided with teeth 62 along its lower edge and adapted to be engaged by a holding latch 63 connected to the pivotally mounted lever 64. The lever is held in such a position that the latch 63 would be normally in engagement with the teeth 62 by means of the spring 65. From this arrangement it will be seen that the lever 60 may be moved in a longitudinal di-

rection with respect to the machine and held in a predetermined position. Pivotally secured to the lever 60 is a longitudinally disposed rod 66 and which extends through the hollow shaft 26 and projects beyond its extreme end and beyond the end of the casting container 28. The end of the rod 66 is provided with two adjusting nuts 67 which are adapted to engage the lever 68 pivotally positioned upon the casting container 28. The lever 28 has a passage therethrough to receive the end of the rod 66 and when the handle 60 is moved forward or backward the lever 68 is also moved forward or backward. The casting container 28 I have shown as comprising the end members 69 and 70. These end members may be round, square, hexagonal or other shapes as desired. Secured to these end members in such a way as to form an enclosure are the sides 71, 72 and 73. The ends and the sides may be secured together either by riveting or welding, both methods of which are well known in the art. The members 71 and 73 are shown as provided with hinges 74 and to these hinges are secured covers 75 and 76 which in turn are provided with hinges 77. The side 73 is shown as provided with latches 78. Longitudinally mounted upon the cover 76 is a slidable bar 79 which is held in position by the straps 80 secured to the cover 76 either by welding or riveting. The slidable bar 79 is provided with tongues 81 which engage with openings through the latches 78 so that when the covers are in closed position and the slidable bar 79 moved so that the latches 81 engage with the latches 78 the covers will be held in a closed position.

In order to operate the movable bar 79, the bar 68 is pivotally secured to the end member 69 as shown in Fig. 7, and the bar 68 also passes through an opening in the bar 79 such that when the bar 68 is moved about its pivotal point the bar 79 will be moved forward and backward and engage and disengage with the latches 78 on the cover 75. The member 68 is operated, as already explained, through the medium of the rod 66 which connects with the lever 60. If the casting container 28 when rotating is brought to rest with the covers 75 and 76 in a downward position and the lever 60 is operated so as to disengage the members 81 from the members 78, then the covers will open, as shown in Fig. 9, by gravity and any castings contained therein will be free to drop out.

When it is desired to load the casting container 28 the position of the container will be reversed from that shown in Fig. 9 and the covers thrown back and the castings loaded within the container and the covers will then be closed and the lever 60 operated to lock the covers in their closed position.

It will be noted that the sides and ends of the container 28 are perforated so as to allow free access of the molten metal to the interior of the container.

In the use of my invention, it is mounted so that the container may be moved downwardly about the pivotal points until the container may be plunged within a tank of molten zinc, tin or other metal desired. The container is first filled with castings to be coated and the covers closed, as already described. The motor 37 may be in operation as it is not necessary to stop the motor in loading and unloading the container 28. When the container has been properly loaded and closed the handle 20 is then operated so as to permit lowering the container 28 into the metal bath and the machine is locked in the lowered position and its longitudinal axis may coincide substantially with the line A—A and locked in this position by releasing the handle 20. The operator then moves the handle 44 downward which will bring the pulley 47 into engagement with the belt 35 thereby tightening the same and as the motor is operating the pulley 42 will be operated and the pulley 33 will be caused to rotate which in turn will rotate the beveled gears 27 and 32 and simultaneously therewith the shaft 26 and the container 28 at a slower speed. After the castings have rotated in the metal bath for a predetermined length of time the operator then disengages the device from its locked oblique position and raises the same slightly from the bath and moves the lever 44 to its upper position which relieves the pressure on the belt 35 and tightens the belt 36 thereby causing the container 28 to operate at a higher speed, which permits the excess molten metal to be thrown off. In order to change the position of the castings within the container while removing the excess zinc, which is desirable in order that they may be better relieved of the excess metal, and especially where castings having hollow places are involved, it is desirable to stop the rotation of the member 28 or to slow down the speed so that the castings may change their position, and this is done by the operation of the member 44 to either its central position and the brake applied, or to its lower position where the speed is reduced, and then the handle is brought up so as to give to the container 28 a high speed. This operation of changing the position of the castings and rotating under high speed can be repeated a number of times thereby thoroughly cleaning the castings, both inside and out, of excess metal.

When such cleaning operation has been completed the machine is swung around with the container 28 over a receptacle and the machine stopped with the covers 75 and 76 in a downward position, and then the lever 130

60 operated to permit the opening of the covers, as already described, or should the container be brought to rest over a receptacle with the covers at an upper position, 5 then a slight operation of the handle 44 to transmit motion to the container 28 will cause the container to open when the covers have reached a lower position.

Having emptied the container, it is again 10 rotated so that the covers 75 and 76 will be in an upward position and the covers are then thrown back and the container loaded 15 with castings, the covers closed and the lever 60 operated to lock the covers closed and the operation of submerging the container in the molten bath is repeated.

If desired a small amount of salammoniac salts or other flux may be thrown into the container, together with castings, and I find 20 that flux applied in this manner is very uniformly distributed over the surface of the castings and has a most beneficial effect.

If desired, the higher speed mechanism may be omitted and the castings cleaned of 25 surplus metal by tumbling about in the container at the slower speed which keeps the castings constantly tumbling about in the container and the excess metal will be removed by drip and the jarring action.

30 The speed of the container while immersed in the coating bath should not be so great as to prevent the coating metal from entering the container through the perforations or other openings and maintain a metal as great 35 or nearly as great as the metal outside of the container. This is advisable so that the coating may be assured to contact for the greatest possible time with all parts of the articles to be coated and hence produce reliability and uniformity. If the container 40 is of the perforated type and the speed is too great there will be, of course, a tendency to prevent the metal from freely entering the container.

45 It will be readily understood that with the axis of the container obliquely disposed, that as the container rotates the castings therein will be raised to a certain point and then they will fall downward and this cycle of 50 operation will be continued as long as the container rotates, and this change of position of the castings within the container tends to reliability in the coating of the product and assures a more uniform coating 55 than though the articles maintained a fixed relative position to each other while submerged in the coating tank. It is also evident that the tumbling of the castings while being rotated within the bath may also be 60 brought about by having the axis of the container in a horizontal position, but if the axis of the container is in a vertical position then the castings, as the container rotates, will not change their relative position re-

gardless of how slowly the container is rotated. 65

When the excess metal has been removed from the articles they may still have a coating in a somewhat softened condition and I find that it is advisable to open the container 70 above a tank containing hot water, or other desirable fluid, which will quench the articles as they fall from the container and thus "set" the coating.

There are, of course, many modifications 75 which one skilled in the art will readily see in a mechanism of this sort, but I do not wish to be limited other than by my claims.

I claim:

1. An apparatus for use in coating articles 80 comprising a tank of coating material, a mounted frame, a rotatable container mounted on the frame, means permitting the frame to pivot in a vertical plane and dip into the tank, means to rotate the container while in and out of the tank and means to open the container at will from a point remote from the container. 85

2. An apparatus for use in coating articles 90 comprising a mounted frame, a rotatable container, means to drive the container, means to change the speed of the container at will, means to stop the container at will, means permitting the frame to be moved from a horizontal position to an oblique position, means to lock the frame in either position at will and means permitting the frame to move about a substantially vertical axis while in a horizontal or oblique position. 95

100 3. A container for use in coating articles comprising in combination, a rotatable shaft, a closed receptacle secured to the shaft and rotatable therewith and having perforated sides, means to lock the receptacle closed and means located at a point remote from the receptacle to open the receptacle. 105

4. A container for use in coating articles 110 comprising in combination, a hollow rotatable shaft, a closed receptacle secured to the shaft and rotatable therewith and having perforations to permit the access of a coating material within the container, means to lock the container closed, means passing through the hollow shaft and extending a 115 distance from the container to open the container from a remote point at will.

5. An apparatus for use in coating articles 120 comprising in combination, a mounted frame, a closed and rotatable container mounted thereon and having a hollow shaft to drive the same, means to rotate the shaft, means to control the rotation of the shaft and container and means located at a point remote from the container to open the container. 125

6. An apparatus for use in coating articles comprising in combination, a mounted

- frame, a closed container, means to lock the container closed, a hollow shaft to which the container is secured, means to rotate the shaft at different speeds, means to control 5 the operation of the shaft, means located at a point remote from the container to control the unlocking of the container, means to pivot the frame from a normally horizontal to an oblique position, means to lock the 10 frame in either position and means to swing the frame about a vertical axis.
7. A coating equipment comprising a tank of liquid coating material, a container for articles to be coated, means to lower the 15 container into the coating material and rotate the container therein about an axis disposed at one angle and to rotate the container about an axis disposed at another angle to remove excess material.
- 20 8. A coating equipment comprising a tank of liquid coating material, a container for articles to be coated, means to lower the container into the coating material and rotate the container therein about an axis disposed 25 at one angle and to rotate the container about any one of several different angles to remove excess material.
9. A self contained apparatus for use in coating articles comprising a frame mounted 30 to pivot in a horizontal and a vertical plane at will, a container rotatably mounted on the frame, a source of rotative power mounted on the frame, and movable with the frame to maintain a fixed position relative to the 35 operative parts on the frame, means connecting the container and source of power to rotate the container and means to stop the rotation of the container at will.
10. An apparatus for use in coating articles comprising a frame mounted to move in a vertical plane about a horizontal axis, a container rotatably mounted on the frame and movable with the frame, means to rotate the container at different speeds at will 40 45 of an operator comprising an electric motor and speed changing mechanism, both mounted upon the frame in fixed position relative to the container, the speed changing mechanism mechanically connecting the motor and container and the container and motor so positioned as to tend to distribute their weight on either side of the horizontal axis.
11. A metal coating apparatus comprising in combination, a stationary tank to hold a metal in fluid state, a container to hold a plurality of articles at one time and to dip 50 55 into the metal bath, a frame on which the container is mounted, means to rotate the container in the bath at a predetermined speed, means to hold the container in the bath with its axis at an oblique angle such that the articles will be raised and dropped alternately within the container and their 60 65 relative position changed as the container rotates and means to change the rate of rotation of the container to a greater speed after the container has been removed from the bath.
12. An apparatus for use in coating articles with metal comprising a tank containing a fluid bath of the coating metal, a container adapted to loosely receive a plurality of castings to be coated and tumbled about within the container, means to mount the container on a support and permit the container to be moved either into or out of the fluid metal at will of the operator and means to rotate the container at will of the operator and tumble the castings about within the container and relative to each other and to the container while the container is submerged in the fluid. 70 75 80
13. A metal coating apparatus comprising in combination, a stationary tank to hold a metal in fluid state, a container to hold a plurality of castings loosely at one time and dip into and out of the metal bath, a frame on which the container is mounted, means to rotate the container both within and without the bath at predetermined speeds and the axis of the container about which it rotates being obliquely disposed while the container is in the bath, the speeds of the container being such that the articles will be raised and dropped alternately and relative to each other within the container as the container rotates within the metal bath and when the container is removed from the bath and rotated, the castings may be either 90 95 100 alternately raised and dropped within the container at one speed or maintained immovable relative to the container due to a higher speed and at will of the operator. 100
14. A metal coating apparatus comprising a tank for a metal bath, a perforated rotatable container for castings and movable either into or out of the bath at will of an operator, means to rotate the container at will of the operator, and means to rotate the container and alternately raise and drop the castings within the container relative to each other and to the container at will of the operator. 105 110
15. A metal coating apparatus comprising a tank for a metal bath, a perforated rotatable container for castings and movable either into or out of the bath at will of an operator, means to rotate the container at will of the operator, and means to either rotate the container and simultaneously therewith alternately raise and drop the castings relative to each other and to the container as the container rotates, or rotate the container and castings simultaneously and together at a high rate to remove superfluous metal and at will of the operator. 115 120 125
16. A coating apparatus comprising a frame mounted to pivot in a vertical plane about a horizontal axis, a rotatable container 130

and a drive mechanism therefor mounted on the frame, means connecting the drive mechanism and the container to impart to the container different speeds at will of the operator without changing the speed of the drive and means to stop the container without stopping the drive mechanism.

17. An apparatus for use in coating articles comprising a frame mounted to pivot in a vertical plane about a horizontal axis

at will of an operator, a container rotatably mounted on the frame, means to impart motion to the container, mechanism connecting the container and said means and means to change the speed of the container at will of the operator.

In testimony whereof I affix my signature.

PATRICK J. KELLEY.
